UNITED STATES PATENT OFFICE.

JOHN GARDNER, OF NEW HAVEN, CONNECTICUT, ASSIGNOR TO THE WINCHESTER REPEATING ARMS COMPANY, OF SAME PLACE.

DESIGN FOR A CARTRIDGE-SHELL.

SPECIFICATION forming part of Design No. 26,676, dated February 23, 1897.

Application filed August 3, 1896. Serial No. 601,565. Term of patent 14 years.

To all whom it may concern:

- Be it known that I, JOHN GARDNER, of New Haven, in the county of New Haven and State of Connecticut, have invented a new Design for a Solid-Head, Metallic, Rim-Cartridge Shell; and I do hereby declare the following, when taken in connection with the accompanying drawing and the letters of reference marked thereon, to be a full, clear, and exact description of the same, and which said drawing constitutes part of this specification and represents a side elevation of a solid-head, metallic, rim-cartridge shell formed in accordance with my design.
- This invention relates to a design for a solid-head, metallic, rim-cartridge shell; and the design consists in the configuration of the shell as shown in the accompanying illustration and hereinafter described.
- My newly-designed shell for solid-head, metallic, rim-cartridges has its body A formed at a point near but slightly forward of its head A' with two shallow, wave-like, circumferential grooves or crinkles a a', located at a right angle to its longitudinal axis, the forward groove or crinkle a' being slightly narrower and also slightly shallower than the rear groove or crinkle a and the two grooves or crinkles being separated from each other

by a distance fairly represented by the width 30 of the groove or crinkle a. The said body A of the shell is slightly tapering and toward its forward end is contracted to form a long, beveled, or sloping shoulder A², which in turn merges into a long cylindrical neck A³. The 35 said head A' of the cartridge-shell is encircled at its extreme rear end by an annular rim A⁴, having a square inner corner which stands at a right angle to the longitudinal axis of the shell. The said rim A⁴ is larger in diameter 40 than any part of the body A of the shell and has its rear edge or corner beveled, as at A⁵.

The essential feature of my design lies in the shallow wave-like grooves or crinkles a and a', when formed and arranged as shown 45 in a cartridge-shell having the other characteristics specified.

I claim—

The design for a solid-head, metallic, rim-cartridge shell as herein shown and described. 50

In testimony whereof I have signed this specification in the presence of two subscribing witnesses.

JOHN GARDNER.
